UNITED STATES PATENT OFFICE.

MORRIS B. OKUN, OF CHICAGO, ILLINOIS.

CHAIR.

1,279,414.

Specification of Letters Patent. Patented Sept. 17, 1918.

Application filed March 13, 1916. Serial No. 83,808.

To all whom it may concern:

Be it known that I, MORRIS B. OKUN, a citizen of the United States, residing at Chicago, in the county of Cook and State of Illinois, have invented a certain new and useful Improvement in Chairs, of which the following is a full, clear, concise, and exact description, reference being had to the accompanying drawings, forming a part of this specification.

My invention relates to chairs and concerns itself more particularly with the production of a chair to which is added a collapsible element or elements which when unfolded provide additional seating space.

My invention is primarily designed to so arrange these collapsible elements that they are entirely hidden from view when in their collapsed or disappearing position.

In the preferred form of my invention I utilize a chair having suitable side arms into which additional collapsible seat structures may be folded so that they entirely disappear from view when not desired for use.

I will describe various forms which my invention may take more in detail by referring to the accompanying drawings in which:

Figure 1 is a perspective view of a chair constructed in accordance with my invention, the collapsible seat structures being shown in their unfolded positions;

Fig. 2 is a view on a reduced scale of the same chair with the seat portions in their collapsed disappearing positions;

Fig. 3 is a side view of the chair shown in Fig. 1 with the seat portions unfolded;

Fig. 4 is a sectional view on line *a—a* of Fig. 3 with the auxiliary seat in its collapsed position;

Fig. 5 is a fragmentary top view partially in section of one of the auxiliary seat structures shown in Fig. 1;

Fig. 6 is a detail view showing the unfolded leg of the auxiliary seat structure;

Fig. 7 is a fragmentary top view illustrating this leg structure;

Fig. 8 is a detail perspective view showing the catch for holding the seat structure in its collapsed position;

Fig. 9 is a view similar to Fig. 1 showing the chair in the form of a rocker, and

Fig. 10 is a detail view illustrating the collapsible leg structure of the rocker shown in Fig. 9.

Referring more particularly to Fig. 1, I show a chair having the seat portion 1, the back portion 2, and the side arms 3 and 4. The side arms are provided upon the interior faces with an upholstering section 5. The side arms are extended downwardly to form legs 6 and 7 and suitable back legs 8 and 9 are provided to complete the normal chair structure. I utilize the space between the arms 3 and 4 exteriorly of the upholstering 5 to provide auxiliary seat structures comprising the seats 10, 10 and back rests 11, 11, which auxiliary seat portions may be folded entirely into the space provided by the arms 3 and 4 outwardly of the upholstering sections 5, all as more clearly apparent from Fig. 4. The back rest 11 of the auxiliary seat structure has preferably a strengthening rim 12 which is pivoted between the upper backward portion of the arms 3 and 4 and the side rails 13 through the agency of pivots 14 and 15. This back portion 11 can thus swing about these pivots 14 and 15 from the disappearing position shown in Fig. 4 to its unfolded position shown in Fig. 1.

The back portion 11 also carries the seat portion 10 which is pivoted thereto by the studs 16 so that this seat structure may be folded contra-clockwise, for instance (Figs. 1 and 3) about these pivots should it be desired to fold up the entire auxiliary seat portion 10. Suitable arms 17 furnish the support for these pins 16. A strengthening bracket 18 is provided to assist in holding the seat portion 10. The forward extremity of the seat portion is provided with a pin 19, which pin enters a slotted portion 20 provided in the leg 6 to guide the said pin 90 and to provide a support for the inner forward extremity of this seat portion 10. The outer forward extremity of the seat portion 10 carries a leg 21, which leg is also arranged in a collapsible manner as more clearly illustrated in Figs. 6 and 7, the seat portion 10 having a pin 22 provided with a head 23 which cooperates with the rounded eye 24 of the leg 21. The pin 22 is square as shown more clearly in Fig. 6 and may enter the recess 25 radiating from the opening in the eye 24 so that as the seat portion 10 reaches its lowermost position the leg 21 being pushed upwardly causes the squared pin 22 to enter the radial slot 25 and thus hold the leg 21 against turning. As soon as the seat portion 10 is lifted upwardly however,

then the pin 22 enters the opening in the eye and the leg 21 may thereafter rotate around into the position shown in Fig. 4. A spring catch 26 is provided upon the back 5 portion and a spring stop 27, the spring stop serving to prevent jarring the seat portion when it is pushed upwardly, and the catch 26 engaging the pin 28 to hold the seat portion in its collapsed position of Fig. 4. 10 When the seat portion is thus elevated and held in position the back portion 11 may then be swung contra-clockwise (Fig. 5) into the disappearing position shown in Figs. 2 and 4 where this collapsed seat 15 structure is held in its collapsed position by having the catch 29 enter the recess 30 provided in the rim 12. The catch 29 is controlled by a suitable push button 31, all of 20 which is more clearly illustrated in Fig. 8. The catch portion 29 is pivoted and held in 25 its locking position by the spring 32 so that whenever the collapsible seat structure is in its folded position the spring 32 forces the catch into the recess 30. To release the auxiliary seat structure the push button 31 is pressed, whereupon the seat may be drawn 30 outwardly and the seat portion dropped into the position shown in Fig. 1.

By referring to Fig. 9, I show my invention as applied to a rocking chair identical in its essential parts to the structure of 35 Figs. 1 to 8, the chair in this event having the rockers 33. The seat portions 10 are provided with legs 34 having rocker elements 35 so that the auxiliary seat structures may be supported by rocking elements.

From what has been described it is

thought the nature of my invention will be readily clear to those skilled in the art.

Having however thus described several 40 forms which my invention may take, what I claim as new and desire to secure by Letters Patent is:

In combination with a chair comprising a bottom frame, a back including side posts 45 extending upwardly from the rear ends of the side rails of the bottom frame, and arms extending upwardly from the forward ends of the side rails of the bottom frame and thence rearwardly to the upper portions of 50 the side posts of the back, of a collapsible seat structure having a part hingedly connected to one of the side posts of the back, said collapsible seat structure when in collapsed condition being of a size and shape 55 corresponding to the size and shape of the recess provided between one of the chair arms, the adjoining side rail of the bottom frame, and side post of the back, and adapted to fold into said recess with its outer face 60 substantially flush with the side faces of the said chair arm, bottom rail, and back post, the thickness of the collapsed seat structure not exceeding the width of said chair arm, back post and bottom rail, said collapsible 65 seat structure being adapted when unfolded to form an additional seat alongside of the main chair structure.

In witness whereof, I hereunto subscribe my name this 8th day of March, A. D., 1916. 70

MORRIS B. OKUN.

Witnesses:

HAZEL A. JONES,
A. LYDA JONES.
